EXHAUST VALVE FOR LAMP MAKING
MACHINES

Daniel Mullan, Kearny, N. J., assignor, by mesne assignments, to Westinghouse Electric and Manufacturing Company, East Pittsburgh, Pa., a corporation of Pennsylvania

Application June 27, 1936, Serial No. 87,702

9 Claims. (Cl. 176—2)

This invention relates to machines for exhausting and gas-filling hollow bodies, and particularly to such used for the manufacture of incandescent electric lamps or similar devices.

5 Exhaust machines used in the lamp making industry usually comprise a rotary conveyor on which a plurality of what are termed exhaust ports are arranged along the periphery of the conveyor. The conveyor is, in fact, a rotary 10 valve including top and bottom valve sections in the form of circular plates.

The valve plates are relatively movable and the relative movement of the plates, by reason of suitable channels and ducts, results in an opening 15 and a closing of vacuum lines to which hollow bodies such as lamp bulbs or the like are connected for an exhausting operation.

It will be readily appreciated that under the continuous operation to which machines of the above type are subjected, the valve sections must be so constructed as to operate with a minimum amount of wear, and further that any concentrated wear on the opposing surfaces of the valve sections results in leakage with the consequent failure to produce the desired degree of 20 vacuum. In the operation of an exhaust machine, a device is exhausted in stages. During this removal of gas from the bulb at each stage, it is necessary for the lamp to be connected to several ports in the valve.

These ports were spaced a selected distance apart and as this distance was necessarily long to provide adequate contact for maintaining a seal, each device was cut off from the pumps for a 35 relatively long period when traveling through a stage of exhaust. This resulted in a drop in the vacuum in the device at each cut-off period and imposed extra work on the pumps to bring the device to the required vacuum.

40 It has been proposed to make the valve sections with elongated slots or ports arranged in close proximity to reduce the distance of cut-off. This expedient, however, reduced the contact area between the ports and after continued use slight 45 grooves would wear between the ports, bringing about a condition which was detrimental to the efficient operation of the machine.

It is an object of the present invention to provide an improved form of exhaust valve in which the time of cut-off is reduced.

Another object of the invention is to provide valve plates for an exhaust machine in which the valve ports are so arranged as to provide a substantially continuous exhausting operation.

55 Another object of the invention is to provide a

valve for an exhaust machine in which multiple valve ports are provided for each device to permit an arrangement whereby such ports may be moved successively into communication with a vacuum line to give a substantially continuous 5 exhausting operation.

Another object of the invention is to provide a valve arrangement in which a substantially continuous exhausting operation may be performed without subjecting the valve members to 10 excessive wear.

Other objects and advantages of the invention will be more clearly understood by reference to the following description together with the accompanying drawings in which:

15 Fig. 1 is a plan view of a machine constructed in accordance with the present invention;

Fig. 2 is a diagrammatic plan view of the machine shown in Fig. 1 but showing the arrangement of the pumps and vacuum lines or manifolds;

Fig. 3 is a view taken on line III—III in Fig. 1;

Fig. 4 is a view taken on line IV—IV in Fig. 3 looking at the under side of the top valve section;

Fig. 5 is a view taken on line V—V in Fig. 4;

Fig. 6 is a view taken on line VI—VI in Fig. 3 looking at the top of the bottom valve section;

Fig. 7 is a view taken on line VII—VII in Fig. 6;

Fig. 8 is a view taken on line VIII—VIII in Fig. 6; and

Fig. 9 is a fragmentary view showing the relative positions of ports in an upper valve section and slots in a lower valve section as one pair of ports is leaving one slot and moving over another.

The present invention may be embodied in any suitable type of exhaust machine such as used for the progressive evacuations of hollow bodies, and particularly in connection with electric vacuum devices such as incandescent electric lamps, radio tubes, and the like.

40 Exhaust machines for the above mentioned purpose are usually provided with two pumps; a preliminary exhaust pump, and what is known as a final exhaust pump. The devices to be evacuated are first connected with the first or preliminary pump, and exhausted as they travel; that is, they are moved from one port to another while on the preliminary exhaust pump.

45 The same procedure is followed when the devices are subjected to the second pump or final exhaust. In exhaust machines as heretofore constructed, a single row of ports was provided and the device moved successively from one port to the other. Thus it was necessary to keep the ports separated to maintain an effective seal.

30

50

55

In accordance with the present invention each conduit for a device is provided with a plurality of ports arranged to communicate with a plurality of slots disposed in two circular rows and in 5 staggered relation. Thus as the conveyor moves and the valve is operated, communication is had with the pump. During the travel of a device from one port to another, one port is closed while the other is opened, and since the ports may thus 10 be widely separated, an effective seal is maintained.

The invention may be applied to an exhaust machine comprising a conveyor, indicated as a whole by the reference character 9, having a central rotatable hub or shaft 10 on which is mounted 15 a carrier plate or flange 11 suitably fastened to the shaft 10 and rotatable therewith.

The shaft is provided with a worm wheel 12 and mounted for rotation in bearings 14 and 14' 20 on a stationary supporting frame or bracket 15. A worm 16 on a shaft 17 is disposed in mesh with worm wheel 12. The shaft 17 is provided with a pulley 18 over which a belt 19 leads to a pulley 21 on shaft 22 of a motor 23. This driving mechanism from the motor provides a continuous drive. It will be understood, however, that an intermittent operation may be provided if desired by 25 using means such as a Geneva drive which is well known and common practice in connection with 30 machines of the present character.

The present invention may be used with either type of machine and the construction shown has been selected for the purpose of disclosing the advantages of the present invention when applied 35 to a machine in which the work parts are moved continuously to attain high-speed production. In the structure shown, a plurality of what are termed exhaust ports 24 are positioned adjacent to and in spaced relation around the periphery 40 of the plate 11. Sixteen ports are shown in the drawings although more or less may be employed. Each port includes a flexible tube 25 to receive an exhaust tube 26 of a bulb 27 suitably supported in a holder 28.

45 A bulb holder and an exhaust port is usually termed a head and the heads are as a whole indicated by the reference numeral 29. The heads are of similar construction and inasmuch as their structure is well known in the art, it is believed 50 that the showing made is sufficient. As the heads move with the conveyor, the supported bulbs are progressively connected to the vacuum pumps by means of a valve comprising a top section 31 and a lower section 32.

55 These valve sections are in the form of rings having flat opposed surfaces 33 and 34 with an interposed oil seal fed through passage 30. The top valve section moves with the shaft 10 and is secured to the plate 11 by dowel pins 35. Pressure springs 36 serve to hold the upper section in firm relation to the lower section which is held stationary by means of dowel pins 37 extending into the said valve section and into the frame 15.

65 As stated, the valve sections which constitute a valve unit, serve to open and close the vacuum lines to the bulbs supported in the heads. This valve also serves to admit gas to the bulb, as when a gas-filled lamp is made, and/or to admit 70 other gases with which the bulbs are flushed in the process of exhaust. Each port 24 is provided with a T-member 38 connecting a conduit 39 to a gas inlet of the valve and with a rubber nipple 41 and a conduit 42 leading to the 75 valve vacuum inlet.

An oil trap 40 is provided between the nipple and the conduit 42. Each nipple is provided with a cut-off means comprising a cam 43 movable about a pin 44 so that at the proper place during movement of the conveyor the cam is operated to pinch the nipple 41 and close the passage through conduit 42, as for example, when the exhaust line is closed and gas is admitted or withdrawn from the bulb, or for other purposes. The opening and closing of the exhaust line by means of pinch cocks is well known in machines of the present type and no detailed description of this operation is given.

A machine of the present type is usually provided with a duplex pump including a preliminary pump 45 and a final pump 46.

The pump 45 is in communication with pump 46 through conduit 47 and intermediate the pumps is a conduit 48 controlled by valve 49 and leading to a manifold 51 having branch conduits 52, 52', 52'', 52'', and 52'', connected to the valve unit. A leak detector 53 is also connected to the manifold 51. This leak detector may be of any well-known type and is not shown in detail. The pump 46 connects with a manifold 54 through conduit 55 which leads to the manifold 54 and is provided with valve 56. This manifold has branch conduits 57, 57', 57'', 57'', 57'', 57'', 57'', and 57'', connected to the valve unit.

30 During the process of evacuation the bulbs are flushed with gases such as oxygen and nitrogen and when gas lamps are made a final filling of argon gas is provided. As shown in Fig. 2, three sources of gas conduits are shown and indicated by the reference characters 58, 59, and 61 controlled by valves 62, 63, and 64 respectively. The gas conduits supply nitrogen, oxygen, and argon, or any other desired gas or gases. These gases may be fed to the valve unit at different stages 40 of the conveyor, but inasmuch as the present valve may be used with or without the introduction of gas in the lamp, further description of the gas flushing or filling is deemed unnecessary.

45 As above pointed out, the present valve unit is constructed to provide a substantially continuous exhaust operation and at the same time to maintain an effective seal between the valve surfaces.

This is accomplished by providing the upper valve section with double ports 65 and 66 connected by a radial passage 67 leading to conduit 42. The lower valve section is provided with an outer row of slots 68', 68'', 68'', 68'', 68'', and 68'', and an inner row of slots 69', 69'', 69'', 69'', 69'', 69'', 69'', and 69''. The slots of one row are staggered with respect to the slots of the other row and at certain positions the ends of the opposite slots are in close proximity to a common radial line so that if, for example, port 66 is being moved over the end of a slot the port 65 will be leaving a slot and the distance between adjacent ends of the slots will be slightly smaller than the diameter of the ports. See Fig. 6 which shows the relative positions of ports 66 and 65 in dotted lines.

55 It will be obvious that the relative positions of the ends of the slots with respect to a radial line is dependent on the diameter of the ports 66 and 65. Thus, as the upper valve section moves, one of the ports 66 or 65 is over a slot in the lower valve section while the other port is closed. This gives a continuous exhaust operation, avoiding any "dead" or cut-off stages.

The relative positions of upper valve ports and the lower valve slots are shown more clearly in Fig. 9 which is diagrammatic. It will be noted 75

that the slots and ports are disposed in what may be termed different concentric circles X , X' , and are so arranged that a row of ports moves over a row of slots. Each pair of ports leading from an exhaust head is arranged so that one port is on a circle concentric with that of the other port, the centers of both ports being disposed on a common radial line Y . As shown, the slots are so arranged that as a port moves from the end of one slot, another port is moving into communication with another slot. The adjacent ends of the slots are thus positioned so that the exhaust head is in continual communication with the pump during a predetermined movement of the valve. With this arrangement of ports and slots, it is possible to maintain an effective seal since the contacting area of the valve sections between the ports and slots is relatively large.

Although the valve slots may be arranged to overlap to such an extent that the exhaust operation is continuous, it will be evident that, if desired, the slots may be so arranged that the bulb may be cut-off from the pump for a brief period by a variation in the arrangement of the ports and slots.

As will be noted from the drawings (see Fig. 1), the bulb is loaded or inserted into an exhaust port at A. The conveyor then moves and the bulb is connected to the preliminary pump 45 through slots $69'$, $68'$, 69^2 , (see Figs. 2 and 6) and is also connected through slot 69^3 with the final pump. The slots $69'$, $68'$ and 69^2 constitute the preliminary exhaust at this stage and, as will be noted, these slots are positioned as above explained and the exhausting operation is continuous. In accordance with the present construction, a leak detector 70 is provided between slots 69^2 and 69^3 .

After the first stage of the preliminary exhaust and the above mentioned short-period connection to the final pump, the conveyor moves the bulb over an inlet 70' for a gas filling and at slot 68^2 the gas is removed. During movement over slots 69^4 , 68^3 , and 69^5 , the bulb is connected to the final pump. At 70^2 the bulb may again be flushed with gas and the gas removed through slot 68^4 which slot connects with the first or preliminary pump.

The final exhaust is obtained by a movement of the bulb over slots 69^6 , 68^5 , and 69^7 and a final relatively long slot 68^6 . The close relation of the slots as above explained, is followed with the final exhaust slots and when the lamp reaches the final exhaust it may be filled with a gas at 70^3 if the lamp is to be gas-filled.

When the lamp has reached its final exhausting position B, it is tipped or sealed-off by any suitable mechanism such as a tipping torch of any well known type. The mechanism for tipping off shown in the present drawings is more clearly shown in copending application Ser. No. 37,111, filed August 21, 1935, by M. E. McGowan and owned by the assignee of the present application. With the mechanism shown, the exhaust tube is heated as it moves between fires 75. A portion of the exhaust tube is softened and is then moved between rotary disks 76 and 77 which compress the softened portion and seal the bulb. When the conveyor reaches station C, the bulb is lifted from the conveyor and fires 78 melt off the excess portion of the tube.

The above described mechanism serves to seal the bulb while it is moving with the conveyor.

Thus the operation of exhausting may be continuous.

As above pointed out, the present machine provides a valve unit which operates to expedite production by avoiding any stationary periods and at the same time the valve unit has the advantage of providing an effective seal at all times whether operating as an intermittent or a continuous machine.

Although a preferred embodiment of the invention is shown and described herein, it is to be understood that modifications may be made therein without departing from the spirit and scope of the invention as set forth in the appended claims.

I claim:

1. A valve unit for an exhaust machine for hollow bodies comprising an upper rotary valve section having a flat surface and a lower stationary valve section having a flat surface, said flat surfaces being disposed in contact, valve ports in said upper surface disposed on a common radial line and in spaced relation, means connecting said spaced ports together for simultaneous connection to a hollow body to be exhausted, arcuate valve slots in said lower valve surface arranged to register with said ports, one of said slots being arranged to move into register with one of said ports when another slot moves out of register with another port.

2. A valve unit for an exhaust machine for hollow bodies comprising an upper valve section having a flat face, a lower valve section having a flat face, means for supporting said sections with said faces in contacting relation, means for effecting a relative rotary movement between said sections about a common axial line, one of said faces having a plurality of ports arranged in spaced relation along a common radial line, the other face having a plurality of slots positioned on different concentric circles, said slots being so arranged that as the valve sections move relatively, one port is moved into communication with a slot as another port moves out of communication with a slot, and means connecting said ports so that the exhausting operation of a hollow body will be continuous during said movement.

3. A machine for exhausting a hollow body comprising a rotary conveyor, a head on said conveyor having an exhaust port, means for making a gas-tight connection between said port and a portion of the hollow body, a rotary valve mounted on the axis of said conveyor, said valve having an upper valve section rotatable with said conveyor and a lower stationary valve section, said valve sections having contacting surfaces, a plurality of valve ports in the surface of the upper valve section disposed on a common radial line in spaced relation, slots in the surface of the lower valve section, one of said slots being arranged to register with one of said valve ports during a movement of said upper valve section, said slots being so positioned that as one port moves from register with a slot, another port moves into register with another slot to produce a continuous exhaust operation while providing sufficient contact area between said surfaces to maintain a seal between the valve sections.

4. A machine for exhausting a hollow body, having a tubular extension, comprising a rotary conveyor, a head mounted on said conveyor, an exhaust port for receiving said extension, a rotary valve unit mounted on the axis of said conveyor, said valve unit having an upper valve section and

a lower valve section, one of said sections being rotatable with said conveyor, said upper valve section having passages, said lower valve section having passages, the passages in the respective sections being so positioned as to register during relative movement of said sections, a conduit connecting said exhaust port to the passages in said upper valve section, gas removal means, means for connecting the passages in the lower section with said gas removal means, the passages in said sections being so arranged that during relative movement of the sections the passages in the respective sections are brought into register, the positions of the registering passages being such that one pair of opposing passages do not move completely out of register until another pair of opposing passages have moved partly into register.

5. An exhaust machine for lamp bulbs comprising a rotary conveyor, an exhaust head mounted on said conveyor, a valve unit including an upper rotary disk valve section and a lower stationary disk valve section, said sections having flat surfaces in contacting relation, means for moving said upper section with said conveyor, an exhaust port in said head to receive an exhaust tube of a bulb, a conduit leading from said exhaust port to said upper section, a pair of ports in the surface of said upper section, a passage 10 leading from said ports to said conduit, an exhaust pump, a conduit leading from said pump to said lower section, a pair of slots in the surface of said lower section, a passage leading from said slots to said last mentioned conduit, said ports and slots being so positioned that as the upper section moves a port is brought into registry with one slot as another port moves out of registry with another slot.

6. An exhaust machine for lamp bulbs comprising a rotary conveyor, an exhaust head mounted on said conveyor, a valve unit including an upper rotary disk valve section and a lower stationary disk valve section, said sections having flat surfaces in contacting relation, means for moving said upper section with, and about the axis of rotation of, said conveyor, an exhaust port in said head to receive an exhaust tube of a bulb, a conduit leading from said exhaust port to said upper section, a pair of radially spaced ports in the surface of said upper section, a passage leading from said ports to said conduit, an exhaust pump, a conduit leading from said pump to said lower section; a pair of slots in the surface of said lower section and disposed at different distances from said axis of rotation, a passage leading from said slots to said last mentioned conduit, said ports being positioned to span the radial distance between said slots, and the latter so located that as the edge of one port moves over the edge of one slot and into registry with the slot the other port moves over the edge of and out of registry with another slot.

7. An exhaust machine for lamp bulbs com-

prising a rotary conveyor, an exhaust head mounted on said conveyor, a valve unit including an upper rotary disk valve section and a lower stationary disk valve section, said sections having flat surfaces in contacting relation, means for moving said upper section with said conveyor, an exhaust port in said head to receive an exhaust tube of a bulb, a conduit leading from said exhaust port to said upper section, a pair of ports in the surface of said upper section, a passage 10 leading from said ports to said conduit, an exhaust pump, a conduit leading from said pump to said lower section, a pair of slots in the surface of said lower section, a passage leading from said slots to said last mentioned conduit, said ports and said slots being so positioned that continuous communication is had between the upper and the lower sections during a movement of the upper section for a predetermined part of its rotary movement, the communication being first between one port and one slot, and then between the other port and the other slot.

8. An exhaust machine comprising means for supporting a hollow body, a rotatable valve section and a stationary valve section, said sections having surfaces in opposed relation, ports in radially spaced relation in the surface of said rotatable section, a conduit connecting said ports with the interior of said body, slots in the surface of said stationary valve section, an exhaust 30 pump, a conduit connecting said slots with said pump, said ports and slots being so arranged that, during a movement of said rotatable section a predetermined distance, first one of said ports is in communication with one of said slots, and 35 then the other of said ports is in communication with the other of said slots.

9. An exhaust machine for lamp bulbs including a valve comprising an upper member having a flat lower surface, and a lower member having a flat upper surface, one of said members being rotatable with respect to the other, said surfaces being in contact, one of said members having arcuate slots spaced circumferentially around its flat surface and staggered alternately on circles of different radii concentric with the axis of rotation of said rotatable member, said other member having ports opening on its flat surface, arranged in pairs, and spaced from said axis of rotation distances corresponding, respectively, 40 with the radii of said concentric circles, so that the inner ports intermittently connect with said inner arcuate slots, and at other times the outer ports intermittently connect with said outer arcuate slots, means connecting said slots to exhaust mechanism, and means connecting said pairs of radially spaced ports together and to lamp bulbs to be evacuated, whereby said bulbs are alternately connected to said mechanism through the inner and outer ports and arcuate 45 slots with which they communicate, in order to improve the exhausting operation.

DANIEL MULLAN.
